UNITED STATES PATENT OFFICE.

JOHN WILLIAM KERN, OF PORTLAND, OREGON.

IMPROVEMENT IN RAILROAD BEDS.

Specification forming part of Letters Patent No. 136,067, dated February 18, 1873.

To all whom it may concern:

Be it known that I, JOHN WILLIAM KERN, of Portland, in the county of Multnomah and State of Oregon, have invented a new and valuable Improvement in Iron Bed for Railroads; and I do hereby declare that the following is a full, clear, and exact description of the construction and operation of the same, reference being had to the annexed drawing making a part of this specification and to the letters and figures of reference marked thereon.

Figure 1 of the drawing is a representation of a bottom view of my invention. Fig. 2 is cross-section of the same.

This invention has relation to railroads, adapted particularly for the use of safety-cars having conical wheels; and it consists in the construction and novel arrangement of a metallic roof-shaped track-bed, substantially as hereinafter described.

Referring to the drawing, A designates the rail, of ordinary form, and B the metallic bed. This bed is composed of sheets of one-fourth-inch boiler-iron, or other suitable material, raised at their middle parts to the angular form or prismoid shape, shown in the drawing, and joined together at their edges, so as to produce an angular ridge, which shall run the whole length of the line, or as far as may be required. At the bases of the inclined sides of the ridge B the sheets are extended laterally to constitute platforms C for the reception of the rails. Flanges d are turned down at the edges of these platforms, and are embedded in the ground, so as to render the bed firm and secure. The rails lie close to the inclined sides of the pyramidal ridge, and are secured by means of the flanges G riveted to the bed and overlapping the base of the rails on the inside, and by the cleats or lugs H riveted to the platforms C and projecting over the outer portions of the said base. The ends of the plates constituting the bed are joined together by overlapping, and angularly corrugating the edges, as shown at I, Fig. 3. Iron ties J are used to bind the sides of the bed and to render the whole structure strong and durable. These ties are bolted to the under sides of the platforms C, and extend crosswise of the track or road.

Before the bed and track are built the road

is properly filled up, so that the bed may rest on a solid foundation and the entire space underneath it occupied.

As before stated, the angular bed is designed for the use of cars having conical wheels. When this form of wheel and bed is employed it is impossible for the cars to get off of the track. The road is therefore absolutely safe against accidents of such character. Provision is to be made, however, for the necessary removal of cars at stations, switches, and the like, by the occasional employment of the ordinary horizontal bed.

The metallic bed is in itself a great improvement upon the old style, being much more durable, stronger, and less liable to get out of repair. The metal protects the road from the effects of water and frost, and may be substituted for wooden ties, or used in connection with them, at a comparatively small additional outlay.

To prevent rust the metal should be coated with some protecting material adapted to the purpose.

What I claim as new is—

1. The improved railroad bed having the angular ridge B located between the rails A, substantially as specified.

2. A railroad bed composed of sheets of metal joined together, raised in the middle to form the ridge B, and extended at the sides to produce rail-supporting platforms C, all substantially as and for the purpose described.

3. The sheets B, constituting the prismoid railroad bed, and joined together by overlapping and angularly corrugating the edges, substantially as specified.

4. The flanges d and cleats H, in combination with a metallic railroad bed having the prismoid metallic ridge B and the rails A, substantially as specified.

5. The iron ties J, in combination with the metallic angular bed B and platforms C, substantially as specified.

In testimony that I claim the above I have hereunto subscribed my name in the presence of two witnesses.

JOHN WILLIAM KERN.
